(57) **CLAIM**

An ornamental design for an electronic article surveillance alarming tag, as shown and described.

DESCRIPTION

FIG. 1 is a top-rear perspective view of the electronic article surveillance alarming tag;

FIG. 2 is a top plan view thereof;

FIG. 3 is a frontal elevational view thereof;

FIG. 4 is a rear elevational view thereof;

FIG. 5 is a left side elevational view thereof, the right side being a mirror image thereof; and,

FIG. 6 is a bottom plan view thereof.

In the drawings, the broken line showing of a lettering depicts environmental subject matter and forms no part of the claim.
